(57) **CLAIM**

The ornamental design for a watch case as shown and described.

DESCRIPTION

1. Watch case
- 1.1: Perspective
- 1.2: Front
- 1.3: Left
- 1.4: Right
- 1.5: Back
- 1.6: Top
- 1.7: Bottom

The broken lines shown in the drawings depict portions of the watch case that form no part of the claimed design; the characteristic features of the design lie in the shape of the main body of the watch case; the product as a whole is used as a watch case; the use of the partial design is the main body of the watch case.
